UNITED STATES PATENT OFFICE.

WILLIAM E. WINE, OF TOLEDO, OHIO.

VENTILATED BAGGAGE AND EXPRESS CAR.

Application filed March 30, 1925. Serial No. 19,356.

My invention relates to new and useful improvements in baggage and express cars and more particularly to the means for providing a maximum ventilation for the same.

6 A goodly number of the express and baggage cars are provided with doors only, no windows being formed in the sides of the cars, and, when these doors are closed, the cars become very "stuffy" and poorly ventilated.

These baggage and express cars are known as "passenger equipment" and are always provided with roof or monitor ventilators, but even with this means of ventilation 15 when the side doors are closed, there is but little circulation of air in the cars.

On the southern roads, especially is it desirable to have as much circulation as possible in these cars, and it is with that end 20 in view that I have successfully installed certain ventilators. These ventilators are of the "Wine type" as shown in my previous Patent No. 1,040,084 of October 1, 1912, although it is to be understood that since that 25 time I have made many improvements on the ventilators and my later type of ventilators possessing the same broad characteristics, may be used.

It will be understood at the outset that 30 ventilators of other types may be used, but the present invention contemplates the installation of ventilators, preferably of my type, as shown in the several views.

One of the objects therefore of the present 35 invention is the installation of a plurality of ventilators of the "Wine type" which are positioned approximately at the bottom of the car so that the air may pass in through these ventilators, and out through the roof 40 or monitor ventilators, thus providing a thorough ventilation throughout the entire length of the car.

Still another object of the invention is to 45 so install the ventilator that it will be thoroughly and rigidly supported within the car, as ventilators which will withstand the strain in railway use must necessarily be relatively heavy.

Still another object of the invention is to 50 install a plurality of ventilators in the sides of the car, and near the bottom thereof, and to rigidly support and brace these ventilators so that after they are once installed they will not become loose and will last for 55 the life of the car.

Still another object of the invention is to

install the ventilators on the opposite sides of the car so that a draft may be created along the bottom of the car as well as permitting the air to circulate through the top 60 of the car.

With these and other objects in view, the invention consists in certain new and novel arrangements and combination of parts, as will be hereinafter more fully described and pointed out in the claims.

Referring now to the drawing showing a preferred embodiment of the invention,

Fig. 1 is a fragmentary side elevation of 70 a portion of a baggage car.

Fig. 2 is an enlarged fragmentary side elevation, the dotted lines showing the manner in which the ventilator is supported.

Fig. 3 is a sectional view taken on line 75 3-3 of Fig. 2 looking in the direction of the arrows.

Fig. 4 is a similar view taken on the same line but with the ventilator removed for the sake of clearness.

Fig. 5 is a horizontal sectional view taken 80 on line 5-5 of Fig. 2.

Referring now more specifically to the figures, there is shown a baggage or express car 1 having the steel plates 2, upright steel braces 3 (shown in dotted lines), 85 a steel reinforcing ledge 4 running longitudinally of the car, and an opening 5 for the door, while ventilators 6 appear in their usual position in the roof 7.

Two ventilators 8 are shown just below 90 the longitudinal strip 4 and slightly above the side sill 9 of the car, and although I have only shown one side of the car, the opposite side might be likewise equipped 95 with these ventilators 8.

Considering the invention in its broadest aspect, as far as the specification has proceeded, it will be seen that though the opening 5 is closed by the door (not shown), air may pass in through the ventilators 8 100 and circulate through the car, and the warm air pass out the ventilators 6, while there will also be a circulation through the ventilators 8 arranged on the opposite sides of the car.

Referring now more particularly to Figs. 2 to 5 inclusive, and at first to Fig. 5, there are shown (to the left of the figure) wooden uprights 10, one of which is grooved or cut out as at 11 for the reception of a side frame 20 of the ventilator, which side frame 110 is secured to the base 12 by means of an up-

turned end or lug 23 which is securely riveted to the said base.

Adjacent the uprights 10, is a steel channel bar 14 within which fits an upright 15, and passing through this wooden upright 15, the channel 14, the uprights 10 and the upturned end 23, of the base plate 12 and the side frame 20, is a bolt 16 for tightly supporting the ventilator and securing it on its one side.

The opposite side of the ventilator is likewise constructed and rigidly held by a bolt 17, this bolt passing through the upright 18 which is similarly grooved as at 19, the bolt then passing through the upturned edge 23' of the base 12 and the side frame 20'. Other bolts 21 are passed through the side frames of the ventilators through the uprights as may be clearly seen in Fig. 2 so that the ventilator is rigidly supported in position and clamped or bolted to the uprights, thus tightly securing the ventilator against any lateral movement in its opening.

As may be seen in Figs. 3 and 4, the base 12 is designed to rest on the beam 22 and has the downwardly extending lip 22' so that any rain or water will drip on the outside of the car rather than soak or impregnate the beam 21.

Secured to the bottom of the car is shown the Z-bar 24 which is riveted to the angle 25, the latter being located behind the metal side 2 of the car. A portion of the side plate at the opening for the reception of the ventilator extends upwardly and under the lip 22' formed on the base of the ventilator. The top plate 27 of the ventilator frame fits within a cut-out portion 28 in the cross beam 29 and a channel 30 is located between this beam and a further beam 31, and likewise a portion 32 of the side 2 is secured to this channel and overlies the outer edge of the top plate of the ventilator as at 33 to shed the rain.

The ventilator in question is substantially the same in principle to that shown in my Patent No. 1,040,084 of October 1, 1912, and comprises the side plates heretofore mentioned, the top and bottom plates of the frame, and a plurality of shutters 34 which are pivotally mounted in bearings 35 on the side frame, these shutters being operated by the handle 36 connected therewith. In Fig. 3 the shutters are shown in their closed position, and it will be understood that a downward movement of the handle 36 will cause the shutters to partly revolve and thus open the ventilator.

These ventilators may be set or locked in an open position and in combination with the roof ventilators will provide a thorough ventilation for the interior of the car.

From the foregoing it will be seen that I have so arranged a plurality of ventila-

tors in passenger equipment cars, that they will provide an efficient means of circulation together with the ventilators which are usually placed in the roof of the car, and even though the doors be closed, the car 70 will be kept cool or at least fresh air will continue to circulate throughout the car.

Cars so equipped are now in use on one of the southern roads and have proved exceptionally cool and well ventilated. 75

Furthermore, the ventilators are rigidly secured in position and the installation is one which is relatively simple.

Having thus described my invention what I claim as new and desire to secure by Letters Patent is:—

1. In combination with a steel side car having ventilators arranged along its roof, a plurality of ventilators fitting within openings in the steel sides of the car, and the uprights adjacent the openings for the ventilators being cut out for the reception of the said ventilators.

2. In an express car having ventilators arranged along the top thereof, metal sides for the said car provided with openings arranged at points slightly above the side sills, the said ventilators having a base overlapping the side plates of the car, a portion of the wooden frame of the car being cut out 95 for the reception of the ventilators, and means passing through a portion of the wooden frame for securely holding the ventilators in position.

3. The combination of a car having a plurality of ventilators along its roof, a plurality of movable type ventilators arranged along the sides of the car and just above the bottom surface of the floor of the car, wooden and metal supporting means adjacent the said ventilators, and means passing through the wooden and metal means for securely fastening the ventilators within the sides of the cars.

4. A car of the passenger equipment type, having a plurality of ventilating means along its top surface, a plurality of ventilators having pivotal shutters disposed along the sides of the car and slightly above the floor of the car, the said ventilators fitting within openings formed in the side plates of the car, the frame work of the car adjacent the opening being cut out for the reception of the ventilator, and channel members adjacent the uprights and means passing through the channel members and the uprights for securing the ventilators in position.

5. A steel car of the passenger equipment type provided with ventilating means along its upper surface, the said steel sides of the car having openings cut therein for the reception of ventilators, the said ventilators supported on cross beams in the framework 125 of the car and secured at its sides to the up- 130

right frames of the car, and the side plates of the car fitting beneath the lower portion of the base of the ventilator, and the side plate of the car extending beyond the outer edge of the ventilator at its top.

5 6. In combination, a car of the passenger equipment type comprising ventilators along its roof of the monitor type, ventilators disposed along the sides of the car of the movable shutter type, the said car having a metal framework and steel sides, said steel sides provided with openings for the reception of said ventilators, vertically and horizontally disposed wooden supporting means adjacent 10 the said openings, and the said ventilators secured and supported by said metal framework and the said wooden means.

15 7. In combination with a steel car of the passenger equipment type, ventilators ar-

ranged along its opposite sides and disposed along the roof of the car, a plurality of ventilators arranged along the sides of the car and located just above the bottom of the car, a plurality of wooden supports for said ventilators, said wooden supports being 20 grooved for the reception of the frame of the said ventilators, the said ventilators extending through openings formed in the steel sides of the car, metal and wooden supporting means for said ventilators and the 25 ventilators so arranged that the lower portion of the frame of the ventilator overlaps the steel side at the openings while the steel sides overlap the outer edge of the upper 30 frames of the ventilators.

35 In testimony whereof I affix my signature.

WILLIAM E. WINE.
